UNITED STATES PATENT OFFICE

VICTOR W. STRODE AND ERNEST W. HAMMER, OF PORTLAND, OREGON

DESIGN FOR AN AEROPLANE

Application filed October 31, 1929. Serial No. 33,243. Term of patent 7 years.

To all whom it may concern:

Be it known that we, VICTOR W. STRODE and ERNEST W. HAMMER, citizens of the United States, residing at Portland, county of Multnomah, and State of Oregon, have invented a new, original, and ornamental Design for Aeroplane, of which the following is a specification, reference being had to the accompanying drawings, forming a part thereof.

In the drawings:

Fig. 1 shows a top plan view;
Fig. 2 shows a front elevation; and
Fig. 3 shows a side elevation.

We claim:

The ornamental design for an aeroplane, as shown.

VICTOR W. STRODE.
ERNEST W. HAMMER.
